FIG. 1.

FIG. 2.

FIG. 2.

Inventor
H. R. Frith,
By Marks & Clark
Atty.

UNITED STATES PATENT OFFICE.

HERBERT RAND FRITH, OF AUCKLAND, NEW ZEALAND.

PUMP BUCKET OR PISTON.

Application filed May 8, 1922. Serial No. 559,402.

To all whom it may concern:

Be it known that I, HERBERT RAND FRITH, a citizen of the Dominion of New Zealand, and residing at Arawa Street, Birkenhead, 5 Auckland, in the Provincial District of Auckland, have invented certain new and useful Improvements in Pump Buckets or Pistons, of which the following is a specification.

This invention relates to buckets and pistons of pumps, engines and the like, and its object is to provide an improved construction thereof, capable of being expeditiously and accurately adjusted, with comparative ease, in cylinders, barrels and the like.

According to the invention, rings capable of expansion are placed around segments which encircle an inverted cone or a tapered ring the latter screwing onto an externally threaded boss. This boss is formed integral 20 with that portion of the bucket or piston, a fixture on the bucket or piston rod, the latter being secured in said boss.

The expanding rings and the segments are held between a flange on the fixed portion of the bucket or piston and solid non-expanding rings.

Bolts screwed into the aforesaid flange pass through the solid rings and also through radial slots, or holes in the segments 30 elongated radially of the bucket or piston.

Adjusting nuts on the bolts are recessed into the uppermost or outer solid rings.

The inverted cone or tapered ring, the external diameter of which decreases towards 35 the flange on the fixed portion of the bucket or piston, has its outer surface formed with a number of separate tapered portions each of which is encircled by a separate set of segments.

The upper or outer end of the inverted cone or tapered ring is provided with means whereby it can be gripped and turned on the boss, such as a series of holes or depressions to take suitable tools.

A stop adapted to be secured on the upper 45 or outer end of the inverted cone or tapered ring and entering a recess therein projects into one of a series of recesses in the inner edge of the uppermost or outer solid ring 50 for the purpose of locking the cone or ring against turning movement.

The invention will be further described with the aid of the accompanying drawing wherein:

Figure 1 is a sectional elevation of the 55 improved bucket or piston, while

Figure 2 is a part plan view and part 60 sectional plan view of same, the part section being taken on the line A—A, Figure 1.

Figure 3 is an elevation of the locking pin 65 or stop.

The bucket or piston comprises an externally screwed boss, 1, formed with a flange 2, and secured on the rod 3 by any approved means.

An inverted cone or tapered ring 4 screws onto the externally threaded boss 1, and is encircled by segments 5 which in turn are surrounded by expansible rings 6.

The lowermost expanding rings 6 and segments 5 are held between the flange 2 on the boss 1 and an intermediate solid or non-expanding ring 7 surrounding the inverted cone or tapered ring 4, while the uppermost expanding ring 6 and segments 5 are held 75 between the intermediate ring 7 and an upper solid ring 7^a.

Bolts 8 which screw into the flange 2 pass through the solid ring 7 and 7^a and 80 through radial slots 9 in the segments 5 and are provided with adjusting nuts 10 adapted to lie in recesses 11 in the upper or outer non-expanding ring 7^a.

The inverted cone or tapered ring 4, the external diameter of which decreases towards 85 the flange 2 on the boss 1, has its outer surface formed with two or more separate tapered portions 12, each of which is encircled by a separate set of segments 5.

In the upper or outer end of the inverted 90 cone or tapered ring 4 holes 13 are provided whereby said ring 4 may be gripped and turned by means of a suitable tool.

A stop or pin 14 (Figure 3) having formed at one end thereof and at right angles thereto a flat plate 14^a, is adapted to lock the tapered cone or ring 4 against turning by inserting the pin 14 into a hole formed by causing any of the semicircular recesses 15 in the inner edge of the upper or outer solid ring 7 to register with a semicircular recess 100 in the outer edge of the inverted cone 4.

The pin 14 is held in position by means of a screw or nut 17 which secures the flat portion 14^a of the stop 14 to the upper or outer end of the inverted cone or tapered ring 4.

To expand the rings 6, the inverted cone or tapered ring 4 is unlocked from the upper or outer ring 7^a by removing the stop 14 from out of the registering recesses 15 and 16, and the nuts 10 on the bolts 8 are loosened.

The inverted cone or tapered ring 4 is then gripped by means of a suitable tool and turned on the boss 2 so as to screw on to the boss 1, this movement causing the segments 5 to open out on the bolts 8 and between the solid rings 7 and 7^a and flange 2, thereby causing the expansion of the rings 6 which encircle or surround the segments 5.

Upon the desired adjustment being made 20 the stop pin 14 is inserted in registering recesses 15 and 16 and secured, thereby locking the inverted cone 4 against turning on the boss 1, while the nuts 10 on the bolts 8 are tightened to clamp the parts together.

If desired more than two expanding rings 25 6 and sets of segments 5 can be employed, additional non-expanding rings 7 being provided, in order that each ring and set of segments 5 will be located between two non-expanding rings or between a non-expanding ring and the flange 2.

What I do claim and desire to obtain by Letters Patent of the United States of America is:—

35 1. A pump bucket or piston comprising a fixed portion with a flange thereon; a tapered ring screwing on said fixed portion; a non-expanding ring; a ring of expansible material enclosing segments which surround 40 the tapered ring; and means for clamping the non-expanding ring, the expansible ring, the segments and the flange together.

45 2. A pump bucket or piston, comprising a fixed portion with a flange thereon; a tapered ring screwing on said fixed portion; a non-expanding ring; a ring of expansible material enclosing segments which surround the tapered ring, and which contain radial slots, bolts screwing into said flange and 50 passing through said radial slots and the non-expanding ring; and nuts on said bolts outside the non-expanding ring.

55 3. A pump bucket or piston comprising a fixed portion with a flange thereon; a ring having two or more tapered portions, screwing on said fixed portion; rings of expansible

material enclosing sets of segments which surround said tapered portions, and contain radial slots; non-expanding rings between said sets of segments and between the expansible rings; an outer non-expanding ring; bolts screwing into said flange and passing through said radial slots and the non-expanding rings, and nuts on said bolts outside the outer of the latter.

4. A pump bucket or piston comprising an externally threaded fixed boss with a flange at one end; a tapered ring screwing on said fixed boss; a non-expanding ring surrounding said tapered ring; a ring of expansible material between said non-expanding ring and said flange; segments containing radial slots, enclosed by said expansible ring and surrounding said tapered ring; bolts and nuts for clamping the flange, the expansible ring the non-expanding ring and the segments together; and means fitted to the tapered ring for preventing turning movement of same on said boss.

5. A pump bucket or piston comprising a fixed portion with a flange thereon; a tapered ring with a vertical recess in its outer edge screwing on said fixed portion; a non-expanding ring with vertical recesses in its inner edge; a ring of expansible material enclosing segments which surround the tapered ring; a fitting secured to the tapered ring having a downwardly projecting pin adapted to be inserted in a hole formed by the recess in the tapered ring registering with a recess in the non-expanding ring; and means for clamping the latter, the segments, the expansible ring and the flange together.

6. In a pump bucket or piston a tapered ring provided with holes or recesses whereby it may be gripped and turned and with a vertical recess in its outer edge; a boss on which said ring screws; a non-expanding ring surrounding said tapered ring, and containing vertical recesses in its inner edge; and a fitting provided with a pin adapted to be inserted in a hole formed by the recess in the tapered ring registering with a recess in the non-expanding ring.

In testimony whereof I have signed my name to this specification in the presence of two witnesses.

HERBERT RAND FRITH.
